UNITED STATES PATENT OFFICE.

HERBERT A. WILLIAMS, OF SOUTH ROYALTON, VERMONT.

SUSPENDERS.

SPECIFICATION forming part of Letters Patent No. 391,218, dated October 16, 1888.

Application filed August 2, 1888. Serial No. 281,828. (No model.)

To all whom it may concern:

Be it known that I, HERBERT A. WILLIAMS, a citizen of the United States, residing at South Royalton, in the county of Windsor and State of Vermont, have invented certain new and useful Improvements in Suspenders; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

The special object of my invention is to improve suspenders by combining therewith a water-proof shield interposed between the fabric or clothing of the wearer and the buckle, so as to prevent the perspiration from rusting the metal of the buckle, thereby soiling the clothes and rotting the suspender and fabric over which it is worn.

Figure 1 of the drawings is a plan view showing the shield applied to a suspender, and Fig. 2 a detail view of the shield.

In the drawings, A represents the suspender-end; B, the buckle, having the hook *b*; and C, the brace-strap, having the ring *c* to couple with the hook *b*.

D is the shield, made of flexible water-proof

material, with an upper large cross-slot, *d*, and two lower oblique slots, *d' d'*. It is attached to the suspender in the following manner: I unhook the buckle-hook *b* from the strap-ring *c*, hold the shield in front of the suspender with the large slot *d* uppermost, pass the suspender-end A and buckle B through said large slot *d*, then pass the brace-strap C through the oblique slots *d' d'*, and finally hook the buckle B to the brace-strap ring *c*.

The practical advantage of my shield is to make the suspender last much longer and in an unsoiled condition, while the shirts of wearer are no longer disfigured with unsightly marks.

Having thus described all that is necessary to a full understanding of my invention, what I claim as new, and desire to protect by Letters Patent, is—

The water proof shield D, having the upper cross-slot, *d*, and the lower oblique slots, *d' d'*, in combination with the suspender-end A and the buckle B, as and for the purpose specified.

In testimony whereof I affix my signature in presence of two witnesses.

HERBERT A. WILLIAMS.
